SCREEN SHADE FOR MOTION PICTURES
AND THE LIKE

James C. Gallagher, Green Bay, Wis.

Application September 21, 1940, Serial No. 357,782

3 Claims. (Cl. 88—24)

The invention relates to improvements in screen shades for motion pictures and the like and has for its primary object the provision of a simple and effective screen shade of the character indicated which is capable of economical production and highly efficient in use.

Other objects will appear hereinafter.

The invention consists of the combinations and arrangements of parts hereinafter described and claimed.

The invention will be best understood by reference to the accompanying drawing forming a part of this specification, and in which

Fig. 1 is a perspective view of a screen shade embodying the invention and shown in position of use;

Fig. 2 is a perspective view of the upper portion of the rear wall of the shade;

Fig. 3 a top plan view of one side of the shade with a portion of the cover broken away; and

Fig. 4 an enlarged side view of one upper corner of the shade.

The embodiment of the invention illustrated in the drawing comprises an elongated sheet of corrugated paper board scored along the lines 10 to facilitate the folding thereof to form a rear wall 11 and two side walls 12 hingedly connected along the scored lines 10. At their front edges the side walls 12 are folded backwardly upon themselves at 13 and secured by wire stitches 13', thereby reinforcing said forward edges.

A cover member 14 also made of a sheet of corrugated paper board is scored along the line 15 adjacent its forward edge to form a downwardly folded securing flange 16 which is inserted in slots 17 provided in the upper reinforced edges of the side walls 12 as indicated and whereby said cover member will be adjustably secured to said side walls 12 to hold the sheet in operative position as indicated in Fig. 1.

If desired a motion picture screen 18 may be formed as indicated directly upon the rear wall 11 or where the screen is provided with a stand

of its own it may be placed within the rear portion of the shade. A slot 19 is preferably provided centrally in the rear wall 11 to facilitate the attachment of certain types of motion picture screens as will be readily understood. Owing to the frictional engagement between the flange 16 on the cover 14 and the slots 17 in the side walls 12, said side walls may be readily adjusted to different angular positions as indicated in Fig. 3. The specific form and arrangement of parts is a simple and effective one for the purpose.

While I have illustrated and described the preferred form of construction for carrying the invention into effect, these are capable of variation and modification without departing from the spirit of the invention. I therefore do not wish to be limited to the precise details disclosed but desire to avail myself of such variations and modifications as fall within the scope of the appended claims.

I claim:

1. A screen shade comprising a single sheet of material scored along parallel lines for bending to form rear and side walls hingedly connected together; and a cover member consisting of a single sheet of material adapted to rest upon and cover the space between said walls and scored adjacent its forward end to form a downwardly bendable flange, there being slots in the upper edges of said side walls to receive said flange.

2. The construction specified in claim 1 in which the forward edges of the side walls are doubled back upon themselves and the slots extended through said doubled back edges.

3. A screen shade comprising a rear wall member; side members hingedly connected with the sides of said rear wall member; and a cover member resting on said wall members and provided at its forward portion with a downwardly extending flange, there being slots in the upper edges of said side walls to receive said flange.

JAMES C. GALLAGHER.
